UNITED STATES PATENT OFFICE.

ARNOLD BIENERT AND EDWIN HACKEL, OF BURGSTEIN, NEAR HAIDA, CZECHOSLOVAKIA.

ADJUSTABLE T SQUARE.

Application filed February 17, 1923. Serial No. 619,679.

To all whom it may concern:

Be it known that we, ARNOLD BIENERT and EDWIN HACKEL, citizens of the Czechoslovakian Republic, and residing at Burgstein, near Haida, Bohemia, in said Republic, have invented certain new and useful Improvements in an Adjustable T Square, of which the following is a specification.

This invention relates to an improved adjustable T-square, in which not only the blade is adjustable with reference to the head at an angle, but on which, besides, an auxiliary ruler is turnably arranged, which is provided with an arched scale and adapted to be adjusted in axial direction as well as at an angle to the blade of the T-square. Thereby, any angle can be quickly and easily drawn with the aid of the improved T-square without any previous construction or calculation. The working with the aid of the improved T-square takes place in a faultless way and saves much time.

The accompanying drawing shows the improved T-square: Fig. 1 is a plan view of the same, Fig. 2 is a longitudinal section on the line A—B of Fig. 1, Fig. 3 is a cross-section on the line C—D of Fig. 1, Fig. 4 is a longitudinal section on the line E—F of Fig. 1, and Fig. 5 is a plan view of the T-square in the position with adjusted blade and adjusted auxiliary ruler.

On the head *a* of the T-square, the blade *b* is adjustably mounted by means of a pivot *c*, a milled-edge nut on the latter serving to fix the two members in any adjusted position. On the blade *b* a segment *d* with a scale thereon is fixed and provided with a slot *e* in which engages a fixed pin *f* of the head *a*. Said pin *f* has a recess *g* and carries on its lower end a blade spring *h*, which at its upper end has a sharp-edged projection *i*. The segment *d* is at the inner side of the slot *e* fitted with a notch *k* in which engages the projection *i* as soon as the blade *b* lies at right angles to the head *a*. Said contrivance serves to fix the T-square in its normal rectangular position, so that said position need not at first be adjusted with the aid of the scale on the segment *d*. Other angular positions of the blade *b* to the head *a* are, however, obtained by means of said scale, in which case the projection *i* is made to face the respective graduation of said scale, the desired angular position being then fixed by tightening the nut on the pivot *c*.

For bringing the blade *b* into an angular position to the head *a*, the projection *i* is preferably pressed out of the notch *k* with the thumb of the left hand, though the disengagement of the projection *i* from the notch *k* takes place automatically by exerting a vigorous pressure on the blade *b* to be adjusted. The pin *f* is provided with a small projecting pointer *f'* which slides over the graduations of the scale on segment *d*.

The blade *b* is at its working edge fitted with a metal lining *l*, which has a projecting ledge *m* with a longitudinal slot *n* therein.

Beneath the blade *b*, an auxiliary ruler *o* is arranged and pivoted to a slide *p* by means of a pin *q*. Said slide has a screw-bolt *r* which passes through the slot *n* and carries a nut *s*. The slide *p* can be shifted along the ledge *m*, the bolt *r* being then guided in the slot *n*. By tightening the nut *s*, the slide *p* with the ruler *o* thereon can be fixed in position. The ruler *o* carries a segmental bow *t* with an angle graduation thereon. The adjustment takes place in such a way that the graduation of the angle desired coincides with the upper edge of the ledge *m*. A clip *u* embracing the ledge *m* and engaging in grooves *v* in the underside of the latter as well as in the slot *n* serves for guiding the segmental bow *t*.

By means of the ruler *o*, lines can be drawn at any desired angle, the vertex of which can be brought to the desired point by a corresponding displacement of the slide *p*.

In the clip *u*, furthermore, a set-screw *w* can be provided in order to fix also the ruler *o* in any desired adjusted position.

When the ruler *o* is not in use, it lies completely below the ledge *m*, so that the blade *b* can be unobstructedly used for drawing lines like with an ordinary T-square.

The metal lining *l* protects at the same time the working edge of the blade *b* against being damaged.

What we claim, is:

An adjustable T-square comprising, in combination, a blade having a longitudinal slot therein, a head pivoted to said blade, a segment with a scale thereon arranged on said blade and having a slot and a notch therein, a pin on said head engaging in said slot, a spring-pressed projection on said pin adapted to engage in said notch, a small pointer on said projection facing said scale, a ledge arranged on the working edge of

said blade, a slide mounted below said ledge and adapted to be adjusted along the latter, an auxiliary ruler pivoted to said slide, a graduated segmental bow provided on said 5 ruler, a bolt on said slide engaging in the longitudinal slot of said blade, a nut on said bolt adapted to fix said slide in any adjusted position, a clip adjustable in the longitudinal slot of said blade and engaging in the under- 10 side of said ledge and adapted to guide said segmental bow, and a set-screw in said clip

adapted to fix said segmental bow and thus said auxiliary ruler in any adjusted position, substantially as set forth.

In testimony whereof we have hereunto 15 set our hands in the presence of two sub-scribing witnesses.

ARNOLD BIENERT.
EDWIN HACKEL.
